INSULATED PAIL OR SIMILAR ARTICLE

Charles O. Bliss, Los Angeles, Calif.

Application July 10, 1956, Serial No. 42,200

Term of patent 14 years

(Cl. D58—17)

FIG. 3

FIG. 1

FIG. 2

FIG. 4

Fig. 1 is a top plan view of an insulated pail or similar article showing my new design;

Fig. 2 is a side view thereof;

Fig. 3 is a bottom plan view thereof; and

Fig. 4 is a fragmentary vertical sectional view thereof, on a larger scale.

I claim:

The ornamental design for an insulated pail or similar article, substantially as shown.
